UNITED STATES PATENT OFFICE.

ROY L. DE CAMP, OF LOS ANGELES, CALIFORNIA, ASSIGNOR TO BAKER IRON WORKS, OF LOS ANGELES, CALIFORNIA, A CORPORATION OF CALIFORNIA.

LIMIT DEVICE FOR ELECTRIC ELEVATORS.

1,258,393.

Specification of Letters Patent.

Patented Mar. 5, 1918.

Application filed September 25, 1917. Serial No. 193,189.

To all whom it may concern:

Be it known that I, ROY L. DE CAMP, a citizen of the United States, residing at Los Angeles, in the county of Los Angeles and State of California, have invented a new and useful Limit Device for Electric Elevators, of which the following is a specification.

This invention pertains to devices of the character designed to work automatically to break the circuit operating the elevator when the load on the elevator moves up and down beyond predetermined levels and when, for any reason, the cable becomes slack as it would, for instance, if the cable broke.

An object of the invention is to produce a device of this character of maximum simplicity and therefore of comparatively slight cost.

Another object is to effect the foregoing by employing a single switch.

Other objects and advantages will appear in the subjoined detail description.

The accompanying drawings illustrate the invention:

Figure 1 is a perspective view of an electrically operated elevator with the invention applied thereto.

Fig. 2 is an end elevation of the invention omitting the slack cable device.

Fig. 3 is an elevation partly in section on line indicated by x^3-x^3 , Fig. 2.

Fig. 4 is a plan view of Fig. 3.

Fig. 5 is an end elevation of the slack cable device, a fragment of the cable drum also being shown.

Fig. 6 is a reduced plan view of the slack cable device.

The elevator cable drum 1 is mounted on a drum shaft 2 which is journaled in standards 2', 3; said shaft being driven through suitable gear reduction by an electric motor indicated at 4. This construction is well

known in the art pertaining to electric elevators and therefore it is unnecessary to illustrate and describe said construction in detail.

The drum shaft 2 is extended as indicated at 5, the extension being provided with screw-threads 6 and being connected by a collar or eccentric hub 7 and bolts 8 to the main portion of the drum shaft. The bolts

8 pass through the hub 7 and into the adjacent end of the main portion of the drum 55 shaft and the hub 7 is keyed at 9 to the shaft extension 5. Journaled on the hub 7 is an eccentric 10 and journaled on the eccentric is an eccentric strap 100 which is connected by a rod 11 to a clevis 12, there being screw- 60 threads 13 on the rod and nuts 14 so that the clevis and rod can be relatively adjusted. The clevis 12 is pivoted at 15 to an arm 16 which in turn is pivoted at 17 to a switch 18 for the motor 4, the operating lever of 65 the switch being shown at 19. Between the arm 16 and the switch lever 19 is interposed a coil spring 20. Thus when the arm 16 is depressed the lever 19 will be moved to open the switch. The type of switch shown 70 in the drawings is well understood in the art pertaining to electric switches and it is therefore unnecessary to illustrate and describe the same in detail herein. It is sufficient to state regarding operation of the 75 switch 18 that when the lever 19 is in the raised position as in Fig. 3 the switch parts are in their circuit-closing positions and when said lever is in the lowered position the switch parts are in their circuit-breaking 80 positions.

Traveling on the shaft extension 5 is a nut 21 which engages the screw-threads 6 and which is shiftably mounted on pins 22 that in turn have their ends fastened in a 85 pin spacer 23 and in the eccentric 10. Thus when the drum shaft 2 is turned in one direction the nut 21 will travel toward one end of the shaft and when the drum is turned in the opposite direction the nut will 90 travel toward the opposite end of the shaft.

Adjustably fastened to the shaft extension 5 by bolts 24 are stops 25, 26, the stop 25 being between the traveling nut 21 and pin spacer 23 and the stop 26 being between the 95 traveling nut 21 and eccentric 10. The stops are provided with clutch teeth 27 adapted to engage clutch teeth 28 at the opposite faces of the traveling nut 21 when the traveling nut is moved sufficiently far in either 100 direction to cause the engagement. It is now clear that when the drum shaft 2 rotates in one direction or another a sufficient number of times the traveling nut 21 will engage one or the other of the stops 25, 26 105 and that when the engagement occurs the

traveling nut 21 will be rotated, thus rotating the pins 22 so as to turn the eccentric hub 7 which in turn operates the eccentric 10 to push the connecting rod 11 and its 5 clevis 12 downward so as to throw the switch lever 19 from its circuit closing position shown in Fig. 3 to its circuit breaking position.

The clevis 12 is provided with a slot 29 10 in which is inserted an arm 30 mounted on a shaft 31. Means operative by slackening of the cable 32 are provided to cause turning of the shaft 31 and said means together with the arm 30 and shaft 31 constitute a slack 15 cable device. These means may be variously constructed and several different types are well known in the art pertaining to electric elevators and to make the operation of the invention clear one such device will be described and is constructed as follows: The shaft 31 is provided with an arm 33 pivoted at 34 to a rod 35 which in turn is pivoted at 36 to a sleeve 37 shiftable on one of a pair of levers 38. The levers 38 are pivoted 20 at one end at 39 to bearings 40 and the other ends of the levers 38 journal a sheave shaft 41 having mounted thereon a sheave 42 over which the cable 32 runs as clearly shown in Fig. 5.

The shaft 31 is provided with an arm 43 30 having thereon a counterbalance 44 tending to turn the shaft 31 in a direction to move the free end of the arm 30 downward in the slot 29 to engage the lower end of the 35 slot and thereby move the clevis 12 downward to cause breaking of the electric circuit the same as previously described. When the cable 32 is taut it holds the sheave 42 toward the drum against the tendency of the 40 counterbalance 44 to move the sheave away from the drum.

It is understood that the switch 18 is connected in the electric circuit controlling the motor 4 so that when the switch lever 19 is 45 in the position shown in Fig. 3 the motor will operate to turn the drum and when the lever 19 is moved downward the electric current supplied to the motor will be cut off so that the drum 1 will come to a stop.

50 The operation of the invention is as follows:

If for any reason the cable 32 becomes slack, when the elevator is in operation, the counterbalance 44 will turn the shaft 31 in 55 a direction to move the arm 30 as indicated by the arrow *a*, Fig. 5, so that the outer end of said arm will engage the lower end of the clevis slot 29 to move the switch lever 19 into circuit-breaking position.

60 Assuming that the motor 4 is in operation to turn the drum in the direction of the arrow *b*, Figs. 1 and 5, to wind up the cable 32, it is clear that if the motor is not thrown out of operation by the operator before the traveling nut 21 engages the stop

25, the engagement of the nut with said stop will cause turning of the nut 21, thus causing operation of the eccentric 10 as hereinbefore noted to move the switch lever 19 into circuit-breaking position.

70

Assuming that the drum 1 is being turned by the motor 4 in a direction opposite to that indicated by the arrow *b* to unwind the cable 32, it is clear that the nut 21 will be caused to travel toward the stop 26 and that, if the 75 motor is not thrown out of commission by the operator before the nut reaches the stop, engagement of the nut and stop will cause the nut 21 to be rotated thus causing rotation of the eccentric as before, but in the opposite 80 direction, so as to cause throwing of the switch arm 19 into circuit-breaking position.

The slot 29 permits motion of the rod 11 with respect to the arm 30 so that the limit device can operate irrespective of the slack 85 cable device. Thus it is seen that means are provided whereby rotation of the drum a predetermined number of times in either direction will throw the switch without affecting the slack cable device which likewise is capable of throwing the same switch.

90

From the foregoing it is clear that the invention employs but one switch for opening the elevator operating circuit in event of the 95 cable becoming slack and also in event of the operator not throwing the motor out of commission before the load on the elevator has reached either one of two predetermined positions due to operation of the cable 32, one position being due to winding of the 100 cable and the other position being due to unwinding of the cable.

95

I claim:

1. The combination with a drum having 105 a cable thereon and a motor to turn the drum, of a switch for the motor, an eccentric operatively connected with the switch, means operative by turning of the drum to move the eccentric, and a slack cable device operatively connected with the connections between the switch and eccentric.

110

2. The combination with a drum having a cable thereon and a motor to turn the drum, of a switch for the motor, a shaft for the drum having an extension provided with 115 screw-threads, a nut to travel along said screw-threads, an eccentric operatively connected with the switch and rotative by turning of the nut, means rotative by the shaft extension adapted to clutch the nut when the 120 nut travels a predetermined distance in either direction, and a slack cable device operatively connected with the connections of the eccentric and switch.

125

3. The combination with a drum having a 125 cable thereon and a motor to turn the drum, of a switch for the motor provided with an arm, a limit device operative by turning of the drum a predetermined number of times in one direction, a shaft, means connecting 130

the limit device and shaft to the switch arm, and means operative by slackening of the cable to cause turning of the shaft.

4. The combination with a drum having a cable thereon and a motor to turn the drum, of a switch for the motor, means operative by turning of the drum a predetermined number of times in either direction to throw the switch, said means including a slotted member, and a slack cable device including an arm inserted in the slotted member.

5. The combination with a drum having a cable thereon and a motor to turn the drum, of a switch for the motor having an operating member, a rod connected with the operating member, means operative by turning of the drum to move the rod, and means

loosely connected with the rod and operative by slackening of the cable to move said rod.

6. The combination with a drum having a cable thereon and a motor to turn the drum, of a switch for the motor having an operating member, a rod connected with the operating member, means operative by turning of the drum in either direction to move the rod, and means loosely connected with the rod and operative by slackening of the cable to move said rod.

Signed at Los Angeles, California, this 7 day of Sept. 1917.

ROY L. DE CAMP.
